UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

DOUBLE-DRUM HOIST.

Application filed April 3, 1924. Serial No. 703,876.

To all whom it may concern:

Be it known that I, CHARLES C. HANSEN, a citizen of the United States, a resident of Easton, county of Northampton, and State 5 of Pennsylvania, have invented a certain Double-Drum Hoist, of which the following is a specification accompanied by drawings.

This invention relates to hoists but more particularly to a power driven hoist of the 10 double drum type, in which either drum may be driven from a common source of power.

Double drum hoists of the small portable type are used in a variety of places, such 15 as slushing in mines, in quarries, in sand pits, coal loading, and in fact in any place where a small high powered, compact unit is desired. These machines must be sturdy and rugged to withstand the hard usage to 20 which they are ordinarily subjected, but on the other hand, they must be as light and compact as possible to enable them to be easily transported from place to place and mounted in any desired or convenient position.

The objects of this invention are to enable 25 two drums, as a haulage and tail rope drum, to be driven from a common source of power by improved devices so as to permit one of 30 the drums to be driven and the other drum to be freely rotated about a common shaft, in accordance with the direction of rotation of the driving means.

In accordance with this invention, a main 35 driver is located on the drum shaft between the two drums of the hoist and a longitudinally extending pawl is pivoted at its center on an axis transverse to the drum shaft so that the pawl is located in a plane 40 passing through the longitudinal axis of the shaft on which the drums are journaled. The pawl is adapted to rock or oscillate about its axis transverse to the axis of rotation of the drums for automatically connecting one or the other of the drums to the 45 main driver, in accordance with the direction of rotation of the driver.

Further objects of the invention will hereinafter appear and the invention is shown 50 in one of its preferred forms in the accompanying drawings, in which

Figure 1 is a longitudinal sectional elevation of a double drum hoist, and

Figure 2 is a transverse section taken on the line 2—2 of Figure 1, looking in the 55 direction of the arrows.

Referring to the drawings, A designates a swivel mounting on which the base plate B is preferably mounted and secured thereto by bolts (not shown). The base plate B 60 upon which the hoist is mounted, is in this instance formed with a saddle clamp C to enable the hoist to be clamped to a column or cross bar, if desired. End frames D are 65 preferably secured to the base plate B in any suitable manner and a shaft E is in this instance supported in the end frames D. The shaft E is preferably provided with thrust bearings F at the opposite ends thereof, and these thrust bearings are suitably journaled in sleeves G. Bearing caps H are in this instance secured to the end frames D over the sleeve G by the tap bolts J to hold the shaft E in its proper position. The shaft E is in this instance rotatable 70 but if desired, this shaft may be stationary. A bearing frame K is preferably secured to the base plate B by the bolts L and a shaft O is suitably journaled in the bearing frame 75 K and a worm P is in this instance formed on the shaft O. Only a portion of the bearing frame K is shown on the drawing, and it is to be understood that the shaft O is suitably connected to be driven by a reversible motor of any suitable type. The 80 details of construction of the bearing box K, the shaft O and the reversible motor are shown and described in my pending application Serial No. 695,623, filed February 28, 1924, and it is not necessary to explain here 85 the arrangement and construction of these parts in detail, as they form no part of the present invention and are merely shown for illustrative purposes.

Flanged drums Q and R are in this instance adapted to rotate about the shaft E and bushings S may be inserted between the drums and the shaft E for taking up wear. A chamber T is preferably formed in each of the drums Q and R and is adapted to 90 be filled with lubricant to supply lubricant to the shaft E through ports U in the bushings S. The chambers T may be suitably closed by a plug V. The drums Q and R are in this instance formed with annular 95 recesses W and X and teeth Y merging into

the cam surfaces *Z* are preferably formed in the outer wall of the recess *W*. Teeth *a* merging into cam surfaces *b* are preferably formed in the outer wall of the annular recess *X* and face in the opposite direction from the teeth *Y*. The teeth *Y* and *a* on the drums *Q* and *R* respectively, constitute drivers for the drums, but it is to be understood that these teeth may be formed on separate members secured to the drums, if desired, because it is not desired to limit the invention to teeth formed on the drums.

A main driver *c* is preferably formed with a transverse slot *d* extending in the direction of the longitudinal axis of the machine. The main driver is in this instance secured to the shaft *E* being suitably keyed at *c* to enable the main driver *c* to rotate with the shaft, although the main driver may rotate about the shaft *E* if desired. The main driver *c* is in this instance in the form of a wheel, having teeth *f* about its periphery which are adapted to mesh with the worm *P*. A suitable housing *g* preferably encloses the main driver *c* and a cap *h* is in this instance connected to the bearing frame *K* by suitable cap bolts *j*. Means are provided for automatically connecting the main driver *c* to one or the other of the drums *Q* and *R* in accordance with the direction of rotation of the main driver and in this instance, a pawl *k* is pivoted at its center on a pin *o* transverse to the axis of the main driver in the slot *d* in the main driver. The pawl *k* is located in a plane passing through the longitudinal axis of the shaft *E* and is adapted to oscillate or rock on the pin *o* for engaging a tooth *Y* or *a*, according to the direction of rotation of the main driver *c*. Upon the reversal of the direction of rotation of the main driver *c*, the cam surfaces *Z* or *b* on the teeth *Y* and *a* respectively, serve to rock the pawl *k* on the pivot pin *o* to engage a tooth on one or the other of the drums *Q* and *R*. When one of the drums is engaged by the pawl *k*, the opposite end of the pawl is free from the adjacent teeth so that when one of the drums is driven the other drum is free to rotate independently of the driven drum about the shaft *E*. Suitable cables *p* and *q* are wound about the drums *R* and *Q* respectively for haulage purposes.

In hoists of this character, it is desirable to exert the braking or checking effect on the drums *Q* and *R* so as to prevent the cable on

the drum, which is free to rotate about the shaft *E*, from unwinding too rapidly, and for this purpose, guide sleeves *r* are secured to the end frames *D* in any suitable manner, adjacent to the outer flange of each of the drums, and plungers *s* are slidably mounted in the sleeves *r*. The plungers *s* are provided with brake shoes *t* having suitable brake linings *u*, and coil springs *v* are located between one end of the plungers *s* and adjusting plugs *w*, so that the brake lining *u* will constantly exert a braking or checking effect on the drums *Q* and *R*.

I claim:

1. In a hoist, the combination of a frame, a shaft supported in said frame, a reversible motor, two drums rotatable about said shaft, a main driver connected to be driven by said motor, opposed drum drivers on said drums and a transversely pivoted longitudinally extending pawl carried by said main driver located and oscillating in a plane passing through the longitudinal axis of the said shaft for engaging one or the other of the said opposed drivers in accordance with the direction of rotation of the said main driver.

2. In a hoist, the combination of a frame, a shaft supported in said frame, two drums rotatable about said shaft, opposed drivers on said drums, a reversible motor, a main driver adapted to be operated by said motor, and a pawl pivoted on an axis transverse to the axis of said main driver and located in a plane passing through the longitudinal axis of the said shaft, and adapted to be rocked on its pivot for engaging one or the other of the said drivers, in accordance with the direction of rotation of said main driver.

3. In a hoist, the combination of a frame, a shaft supported in said frame, two drums rotatable about said shaft, opposed drivers on said drums, a reversible motor, a main driver adapted to be operated by said motor, and a longitudinally extending pawl transversely pivoted at its center to said main driver and located in a plane passing through the longitudinal axis of the said shaft and adapted to be rocked on its pivot for engaging one or the other of the said drivers, in accordance with the direction of rotation of said main driver.

In testimony whereof I have signed this specification.

CHARLES C. HANSEN.
